REACTOR.

Application filed May 11, 1925. Serial No. 29,287.

Our invention relates to electrical protective devices and particularly to reactors for transformers and other electrical devices.

One object of our invention is to provide a reactor of the through conductor type.

Another object of our invention is to provide a reactor that shall be free from coil windings.

Another object of our invention is to provide a simplified form of reactance that may be easily adjusted to suit a wide range of requirements.

It is also an object of our invention to provide a simple and easily adjusted reactor that may be used in conjunction with a transformer for increasing the reactance of the transformer circuit.

A further object of our invention is to provide means for accomplishing the parallel operation of two or more transformers whose impedances are dissimilar without the necessity of any change in the transformer windings.

In the accompanying drawings,

Figure 1 is a face view of a reactor embodying our invention.

Fig. 2 is an edge view thereof.

Fig. 3 is a diagrammatic view of circuits and apparatus showing our reactor applied to a bank of transformers of unequal impedances.

Fig. 4 is a view showing parallel-connected transformers that are balanced by means of our reactors.

Referring particularly to Figs. 1 and 2, our invention comprises, in general, a reactor or balancing coil that is made up of a plurality of stamp'd laminations 1 clamped between end frames 2 by bolts 3 permitting an increase or decrease in the number of laminations 1 and having a straight bushing 4 extending longitudinally into the central portions of the laminations and end frames.

The bushing 4 is preferably formed with either one or two openings 5, although any desired number of openings may be employed as the opening for the bushing 4 through the end frames 2 and the laminations 1 may be of any desired size. The laminations 1 may be provided with one or more air gaps 6, if desired, one only being shown. The disposition of the air-gaps 6 has a pronounced effect upon the noisiness of the reactor. When the structure is employed as a re-

actor, the air gap 6 is made use of, but when employed as a balancing coil, it is preferable to omit the use of an air gap. The reactor is energized by the electrical conductor or conductors extending through the opening or openings in the bushing 4.

Referring to Fig. 3, the primary windings of the transformers 7 and 8 are connected in parallel circuit and their secondary windings 9 and 11 are similarly connected in parallel circuit and are provided, at their ends, with double leads 12. The transformer 7 has a lower impedance than the transformer 8 and, accordingly, a reactor is placed about the leads of the transformer 7 in order to effectively increase the impedance of that transformer, as compared to the impedance of transformer 8, and thereby equalize the current supplied by the two transformers.

Referring to Fig. 4, we have shown the reactor employed as a balancing coil to equalize the current delivered by parallel-connected secondary windings 13 and 14 of transformer bank. In this application of our invention, one of the conductors from the winding 14 is threaded through an opening 5 so that the current will traverse the reactor in one direction and a conductor from the winding 13 passes through another opening 5 in the reactor so that its current will traverse the reactor in a direction opposite to that of the winding 14. The two conductors are then connected at a point exteriorly of the reactor. Under normal operating condition of a balanced load between the windings 13 and 14, the impedance offered by the reactor to the currents from both windings is the same. However, should either of the windings 13 or 14 tend to deliver more current than the other winding, the impedance of the reactor to that current increases, thereby causing that current to decrease and, at the same time, causing the other winding to increase the current delivered by it. In this construction, the currents delivered by the windings 13 and 14 magnetically influence each other through the reactor to maintain equal values. In other words, the reactor acts as an equalizer.

It will be seen that we have devised a simple and easily adjusted reactor whose reactance may be increased or decreased to suit the requirements of the apparatus with which it is used.

We do not wish to be restricted to the specific arrangements of parts herein set forth, as various modifications thereof may be effected without departing from the spirit and scope of our invention. We desire, therefore, that only such limitations shall be imposed as are indicated in the appended claims.

We claim as our invention:

- 10 1. In an electrical reactor, a plurality of laminations, a pair of end frames, means for clamping the end frames and laminations together, a bushing having a plurality of straight passageways extending longitudinally of the reactor, and electrical conductors constituting portions of electrical circuits in said passageways whereby the current traversing one of the conductors influences the value of the current traversing 20 the other conductor or conductors.
- 15 2. In an electrical reactor, a plurality of laminations, end frames therefor, means for clamping the end frames to the laminations, insulating means extending longitudinally 25 of the reactor and a winding for the reactor comprising conductors within the insulating means and in mutual inductive relation.
- 20 3. In an electrical reactor, a plurality of laminations, end frames therefor, means for clamping the end frames to the laminations, a straight bushing having a plurality of passageways extending longitudinally of the reactor and windings for the reactor comprising conductors within the bushing 35 whereby the currents traversing the several conductors influence the value of one another.
- 25 4. In a device for adding reactance to a single conductor system, a bushing for the reception of a conductor of said system, a plurality of end frames for supporting the bushing, adjustable clamping means for the end frames and a plurality of laminae surrounding the bushing and confined between 40 the end frames, each of the laminations being provided with an air-gap extending in a radial direction to the bushing and in predetermined angular relation to the air-gaps of adjacent laminae.
- 30 5. In a reactor, the combination with a current-carrying conductor, of a group of separable magnetizable members of a magnetic circuit inductively related with said conductor, the flux induced in said magnetizable members reacting solely on said conductors, and means for maintaining said magnetizable members in assembled relation, said means comprising a detachable structure whereby the number of magnetizable 45 members associated therewith may be varied in accordance with the magnitude of the reactance to be added to the circuit in which said conductor is included.
- 35 6. In a reactor, the combination with a current-carrying conductor, of a group of separable magnetizable members of a magnetic circuit inductively related with said conductor, said magnetizable members functioning solely to increase the number of lines of force around said conductor, and a frame 50 for said magnetizable members, said frame comprising detachable members whereby the number of magnetizable members associated therewith may be varied in accordance with the magnitude of the reactance to be added 55 to the circuit in which said conductor is included.

6. In a reactor, the combination with a current-carrying conductor, of a group of separable magnetizable members of a magnetic circuit inductively related with said conductor, said magnetizable members functioning solely to increase the number of lines of force around said conductor, and a frame 70 for said magnetizable members, said frame comprising detachable members whereby the number of magnetizable members associated therewith may be varied in accordance with the magnitude of the reactance to be added 75 to the circuit in which said conductor is included.

7. In a reactor, the combination with a current-carrying conductor, of a group of separable magnetizable members of a magnetic circuit inductively related with said conductor, said magnetizable members functioning solely to increase the number of lines of force around said conductor, a frame comprising end plates for said magnetizable 80 members, and a plurality of detachable elements for maintaining said end plates and magnetizable members in assembled relation whereby the number of magnetizable members may be varied in accordance with the 85 magnitude of the reactance to be added to the circuit in which said conductor is included.

8. In a device for adding reactance to a single conductor system, the combination 90 with a current-carrying conductor of said system, of a group of magnetizable members of a magnetic circuit inductively related with said conductor, said group of magnetizable members functioning solely to increase 95 the number of lines of force around said conductor and comprising an air gap impeding saturation thereof, and means for maintaining said magnetizable members in 100 assembled relation.

9. In a reactor, the combination with a current-carrying conductor, of a group of separable magnetizable members of a magnetic circuit inductively related with said conductor, said magnetizable members functioning solely to increase the number of lines of force around said conductor and comprising aligned air gaps impeding saturation 105 thereof, and a frame for said magnetizable members, said frame comprising detachable members whereby the number of magnetizable members associated therewith may be varied in accordance with the magnitude of the reactance to be added to the circuit in which said conductor is included.

110 9. In a reactor, the combination with a current-carrying conductor, of a group of separable magnetizable members of a magnetic circuit inductively related with said conductor, said magnetizable members functioning solely to increase the number of lines of force around said conductor and comprising aligned air gaps impeding saturation thereof, and a frame for said magnetizable members, said frame comprising detachable members whereby the number of magnetizable members associated therewith may be varied in accordance with the magnitude of the reactance to be added to the circuit in which said conductor is included.

115 In testimony whereof, we have hereunto subscribed our names this 4th day of May, 1925.

JOSEPH S. HEBREW.
EDWARD E. ROSS.
